UNITED STATES PATENT OFFICE.

FRANK O. HAUBNER, OF NEW YORK, N. Y.

DESIGN FOR WARP-NET FABRIC.

SPECIFICATION forming part of Design No. 30,709, dated May 2, 1899.

Application filed April 3, 1899. Serial No. 711,608. Term of patent 7 years.

To all whom it may concern:

Be it known that I, FRANK O. HAUBNER, a citizen of the United States, residing at New York, in the borough of Manhattan and State 5 of New York, have invented and produced a new and original Design for Warp-Net Fabrics, of which the following is a specification, reference being had to the accompanying drawing, forming a part thereof.

- 10 The drawing shows a plan of a portion of a warp-net fabric embodying my design. The leading or essential feature of my design for warp-net fabrics is a series of inter-
- 15 lying zigzag strands, some of the V-bends of the strands being wider than others, so that an open-work is produced.

The fabric is provided with a series of in-

terlying zigzag strands *a*, in which all of the V-bends which extend in one direction are narrower than all of the V-bends which extend in the opposite direction, so that open-work is formed. Cross-threads *b* pass across or around the angles of the V-bends.

What I claim is—

The design for a warp-net fabric, as herein 25 shown and described.

In testimony that I claim the foregoing as my invention I have signed my name in presence of two subscribing witnesses.

FRANK O. HAUBNER.

Witnesses:

PAUL GOEPEL,
M. H. WURTZEL.
